DESIGN FOR A FERRULE FOR HOUSEHOLD UTENSIL HANDLES AND THE LIKE

Clarence R. T. Hess, Prairie View, Ill., assignor to
Edward Katzinger Company, Chicago, Ill., a
corporation of Illinois

Application January 22, 1937, Serial No. 67,227

Term of patent 7 years

To all whom it may concern:

Be it known that I, Clarence R. T. Hess, a citizen of the United States, residing at Prairie View, in the county of Lake and State of Illinois, have invented a new, original, and ornamental Design for a Ferrule for Household Utensil Handles and the Like, of which the following is a specification, reference being had to the accompanying drawing, forming part thereof.

Fig. 1 is a side elevation of a ferrule embodying the present design;

Fig. 2 is a front elevation thereof;

Fig. 3 is a cross sectional view thereof taken on line 3—3 of Fig. 1.

I claim:

The ornamental design for a ferrule for household utensil handles and the like, as shown.
